ELECTRON GUN

James A. Hall, Elmira, N. Y., assignor to Westinghouse Electric Corporation, East Pittsburgh, Pa., a corporation of Pennsylvania

Application August 14, 1953, Serial No. 374,240

5 Claims. (Cl. 313—82)

My invention relates to cathode-ray tubes and in particular relates to an improvement in the cathode-ray guns which project electron beams onto the fluorescent screens of such tubes.

The electron beams in cathode-ray tubes are projected by an assemblage of electrodes known as an electron gun such as is diagrammed in Fig. 1 which comprises a heated cathode 1 having a control electrode 2 enclosing its electron-emissive end-portion except for an aperture 3. Facing the control electrode 2 is a screen-electrode 4 comprising a disc 5 with an aperture 6 aligned with aperture 3, and a cylindrical wall which may have a rolled edge 7. Facing the wall 7 is the circular edge of another cylindrical member 9 which may be joined to cylindrical member 13 by flanges 11 and 12. The member 13 is closed at its remote end by a disc with an aperture 17 located on the axis of member 13. To provide for an ion trap of a type now widely used in television picture tubes, the rim of the screen-grid electrode wall 7 and adjacent edge of member 9 may be slanted at an angle of about 10 to 13 degrees relative to the plane perpendicular to the axis of the screen electrode 4. The electrostatic field produced between these electrodes at the normal operating voltages bends the unwanted beam of negative ions away from the axis of electrode 9 so that it cannot pass through the aperture 17, and therefore cannot reach and damage the fluorescent screen of the picture tube. The electron beam is caused to follow a curved path through the aperture 17 by the action of a magnetic field in the direction perpendicular to the plane of the diagram. This magnetic field is customarily supplied by a magnet whose pole pieces are located approximately over the screen-grid electrode 4. The path of the heavier negative ions is little affected by this magnetic field.

C coaxial with cylinder 13 but spaced therefrom by a gap is a cylinder 14, closed at its nearer end by a disc having an aperture 18 located on its axis. The discs in parts 13 and 14 may have various shapes, but are usually of the dished shape indicated in Figure 2. The cylinders of parts 13 and 14 may be parallel sided or may have a section of smaller diameter near the closed ends of these parts.

Surrounding the gap between cylinders 13 and 14 is a larger cylindrical sleeve 16 called the focussing electrode. Sleeve 16 is insulatingly supported coaxially and approximately symmetrically relative to the gap between cylinders 13 and 14. In some designs, a similarly located ring or disc with centrally located aperture is provided instead of the sleeve 16 to produce the focussing field.

2

The outer end of cylinder 14 customarily has a wide flange which is provided with springs 15 of flexible metal which engage the walls of the cathode-ray tube and assist in positioning the cathode-ray gun structure centrally therein. While cylinders 9 and 13 may be coaxial, they are customarily joined so that their axes intersect at an angle of 3 to 5.5 degrees, crossing in the plane of the flanges or other joining means, so that the electron beam after completing its curved path in the region of the magnetic and axially unsymmetrical electrostatic fields, will follow a path along the axes of parts 13, 14 and 16.

The cylinders 2, 4, 9, 13 and 14 are usually all of the same inside diameter, the cathode 1 is insulatingly supported within the control electrode 2 and all electrodes are provided with leads by which electrical potentials may be impressed on them from voltage sources outside the cathode-ray tube. The above-described assemblage of cylinders constitutes an electron-lens system by which the electrons emanating from cathode 1 may be focussed into a spot of small diameter on the fluorescent screen 19 at the remote end of the cathode-ray tube 20 which forms a vacuum-tight enclosure for the above-described structure as widely used today in television picture tubes. The electron beam is projected along the axes of electrodes 13, 14 and 16 and is then deflected by two sets of mutually perpendicular magnetic deflecting coils 21 and 22 to scan the picture screen 19 in a manner now well known.

30 The electron optical characteristics of this assemblage depends upon the relative dimensions and spacings of the component cylinders, sleeves and diaphragm apertures, and on the magnitudes of the electrical potentials impressed on them. It may be noted that dimensions 35 and magnitudes in this electron-optical system are relative, so that an assemblage in which all dimensions are the same as those of another assemblage multiplied by the same factor will produce similar optical patterns in the latter provided it is supplied with electrical potentials 40 which are the same as those impressed on the former. The dimensions in the Fig. 1 assemblage may therefore be expressed as ratios to the inside diameter D of cylinder 2. While this or a similar system is widely used in most recent electrostatically focussed picture tube guns, 45 a number of undesirable features have been found which I will now point out.

A. The bias voltage on control electrode 2 is made manually variable to enable control of picture brightness by varying the current in the electron beam. The potential needed for cylinder 16 to maintain the best spot focus, hereinafter called the focus voltage, becomes rapidly more negative as the picture brightness, and hence beam current, is increased. This focussing voltage is customarily derived from the supply which furnishes 50 250 to 350 volts D. C. for anode power for the receiving type tubes in the receiver. Thus the range of adjustment available may be insufficient to maintain the best focus with variation of picture brightness.

B. The voltage applied to control electrode 2 is modulated by the signal from the video amplifier of the television receiver to vary the brightness of the fluorescent spot on the picture tube screen by varying the beam current as each picture element is scanned. In tubes using electrostatically focussed guns of the prior art the 55 size of the fluorescent spot becomes rapidly larger and

the detail in the reproduced picture less distinct as the electron beam current is increased. This effect, known colloquially as "blooming," causes loss of detail in picture highlights. I television reception in weak signal areas, stray signals originating in the receiver circuits cause a random pattern of white dots to be superimposed on the reproduced picture. This type of interference is known to workers in the field as "snow." The increase of fluorescent spot size with increasing brightness then becomes especially undesirable since the white dots will be large and much more objectionable to the viewer.

C. The potential applied to electrodes 9, 13, and 14, hereinafter called the anode potential, which is usually between 10 kv. and 18 kv. positive with respect to the picture tube cathode, is subject to wide variation during receiver operation. This variation is due both to fluctuations in the voltage supplied by the domestic power-supply lines and to variations in the load conditions within the television receiver since the anode potential supply has very poor regulation. A drop of 1000 or more volts for a 200 microampere change in picture tube anode current is typical of present practice. The anode supply voltage may also vary during the life of the receiver due to the gradual deterioration with life of other tubes and components in the receiver.

These variations tend to degrade picture definition since the focus voltage required to maintain best picture definition becomes more negative as the anode potential is decreased, in the order of 50 volts for every kilovolt change in the anode voltage.

This effect becomes much more objectionable in light of A and B above, since these effects all tend to make the focussing voltage required more negative. Further, the causes listed tend to add, since lowering the anode voltage tends to make the picture dim, while attempts to increase picture brightness by changing the bias voltage applied to the control electrode to increase the tube current will further decrease the anode voltage because of the poor power supply regulation.

D. The focus voltage required becomes rapidly more negative as the voltage applied to the screen grid electrode 4 is increased. A 100 volt change in this voltage will cause a 200 volt change in the focus voltage. The percentage of the electrons leaving cathode 1 which finally arrive at the fluorescent screen is a function of the operating voltages. At high brightnesses, the electron beam diameter in the gun may exceed the diameter of aperture 17, and further attempts to increase the brightness will increase the percentage of electrons which are intercepted by the end of electrode 13. For a given current of electrons from the cathode, the beam diameter at this point is increased if the voltage on screen-grid electrode 4 is increased, or if the anode voltage on electrodes 9 and 13 is decreased. Since high picture brightness is desired and since only the electrons which reach the fluorescent screen contribute to picture brightness, the electron gun must be designed so that little if any of the electron beam is intercepted by electrode 13 under the least favorable conditions of operation expected in the field.

E. To find a good market, cathode-ray tubes must fit a wide variety of different television receivers, and the magnitudes of the screen-grid (electrode 4) and anode (electrodes 9, 13, 14) supply voltages varies widely between television sets of different manufacturers. Typical ranges for these voltages are 275 to 500 volts for the screen-grid voltage and 10 to 18 kilovolts for the anode voltage. Furthermore, the picture brightness requirements considered necessary by various receiver manufacturers range from 12 to 70 foot lamberts. Because variations in picture brightness, screen-grid voltage and anode voltage all change the focus voltage required by the picture tube, and because the range of focus voltage supplied in a television receiver is small (or zero in some cases) it was impossible to design one electrostatically focussed cathode-ray tube which would perform

satisfactorily in all receivers designed for this type of tube. As a result, cathode-ray tube manufacturers find it necessary to build two or three tubes actually differing from each other for each nominal tube type.

F. The magnetic field impressed near the screen-grid 4 as part of the ion-trapping device is of non-uniform intensity across the region traversed by the electron beam; in electron guns of prior design, the cross section of the beam is distorted from a true circle, the shape of the light spot produced on the picture screen is distorted from a circle and picture resolution is degraded. Both the uniformity and strength of this magnetic field vary between sets of different manufacture, so that a compensating non-uniform electric field cannot be used to correct this beam distortion.

G. In the electron guns described, slight non-uniformities in the electric field between electrodes 4 and 9 distorted the cross section of the beam from a circle, with loss of picture definition. These field non-uniformities were both those caused by slight distortions of electrodes 4 and 9, and the general field asymmetry in this region required for the ion-trapping action.

One object of my invention is accordingly to provide a new and improved structure for cathode-ray tubes.

25 Another object is to provide a new and improved type of electron gun for cathode-ray tubes.

Another object is to provide a new and improved type of electrostatically focussed electron gun for cathode-ray tubes.

30 Another object is to provide a new and improved type of electron gun of the so-called low voltage electrostatically focussed type for cathode-ray tubes.

Another object is to provide a cathode-ray gun of this type in which the focussing of the beam shall be less sensitive to variations of anode potential relative to the cathode than cathode-ray guns of the prior art.

Another object is to provide a cathode-ray gun of this type in which variation of the focus voltage required to compensate for variations in the screen-grid voltage shall be greatly reduced.

Another object is to provide a cathode-ray gun of this type in which variation of the focus voltage with bias voltage of the control electrode shall be smaller than that of the prior art.

Another object is to produce a cathode-ray gun in which variation of the focus voltage required to compensate the effect on beam focus of variations in picture brightness shall be less than in conventional cathode-ray tubes operating in conventional receivers.

50 Another object is to provide a cathode-ray gun in which the size of the light spot on the picture-screen is smaller for a given gun length than in cathode-ray guns of conventional type.

Another object is to produce an electrostatically focused cathode-ray gun in which substantially all focussing occurs in a single electron lens.

Still another object is to produce a cathode-ray gun in which focussing in the electron lens comprising the screen grid and the first anode is reduced virtually to zero.

Still another object is to produce a cathode-ray gun in which the percentage of the electrons emitted by the cathode which arrive at the picture screen is little affected by variations in the anode voltage or the screen-grid voltage.

65 Yet another object is to provide a cathode-ray gun which is less sensitive to variations in the magnetic field comprised in the ion trap than are prior art cathode-ray guns.

70 Yet another object is to provide a cathode-ray gun in which larger tolerances in the symmetry of the electron lens comprising the screen-grid first anode may be permitted than in cathode-ray guns of the prior art.

Still another object is to produce a cathode-ray gun which is less sensitive to non-uniformity within field of the ion-trap magnet than are cathode-ray guns of the prior art.

Yet another object is to produce a cathode-ray gun in which the focussing effect at the first electron lens, adjacent the screen-grid electrode, is reduced and the focussing effect of the second electron lens, between the anode cylinders and focussing electrode, is normal.

Other objects of my invention will become apparent upon reading the following description taken in connection with the drawings in which:

Figure 1 is a schematic view showing the relation of the cathode-ray gun embodying the principles of my invention to the other structural elements of a cathode-ray tube.

Fig. 2 is a schematic view partly in section of a cathode-ray gun of the prior art; and

Fig. 3 is a similar view of a cathode-ray gun embodying the principles of my invention.

Fig. 1 is believed to have already been described sufficiently so that further description of it is superfluous.

Referring to Fig. 2 the cathode 1 comprises a metal cylinder 30 having a cupped end 33 surfaced with thermionically-emissive material which is heated by an electrical heater-winding 23. The cathode is supported by a ceramic collar from the control electrode 2, which has its end facing cupped end 22 closed except for central aperture 3. The distance from the emissive surface on cathode 1 to the aperture 3 is about 0.01 D; the other important dimensions of cathode 1 and control electrode 2 are tabulated below.

Facing the aperture 3 in control electrode 2 is the central aperture 6 in the flat end of screen-grid 4, and facing the other end of the latter is the open end of cylindrical first-anode-section 9; control electrode 2, screen-grid 4 and first-anode-section 9 are rigidly interconnected by two or more rods of insulating material 25, 26 to which their support-arms 27 are attached. The adjacent edges of electrodes 4 and 9 are in parallel planes inclined to a plane perpendicular to the axis of screen-grid 4 by an angle of about 10 to 13 degrees, and the edge of screen-grid 4 may be rolled over as shown or may be merely cut and polished to remove sharp edges and burrs which might cause local distortions of the electrostatic field.

The right-hand side of first-anode-section 9 is joined by flanges 11, 12 or some other suitable joining means to section 13 which has its remote end closed except for a central aperture 17 which is aligned with the central aperture 18 in the closed end of anode-section 14. The common axis of electrodes 4 and 9 may be inclined by about 3 to 5.5 degrees to the common axis of electrodes 13, 14 and 16, intersecting the latter at a point in the plane of the flanges or other joining means 11, 12. The anode-sections 13 and 14 are electrically interconnected, and are rigidly interconnected mechanically by a set of insulating rods 28, 29 to which their support arms 31 are attached. A sleeve or focussing electrode 16 affixed to support rods 28, 29 surrounds the space between apertures 17 and 18. A wide flange 32 to which are attached flexible spring-plates 15 is provided at the right-hand end of anode-section 14. The apertures 3, 6, 17 and 18 are positioned along the curved path which electrons will travel through the electrostatic fields of these electrodes and the magnetic field of an ion-trap magnet (not shown) mounted outside the tube near electrode 4.

In-leads through the wall of tube 29 make it possible to impress the desired potentials on the electrodes 1, 2, 4, 9, 13, 14, 16 and 23. Thus cathode 1 may be grounded; control electrode 2 may be impressed with signal voltages and with a variable negative bias to control brightness of the picture on screen 19; screen-grid electrode 4 with a fixed position voltage usually between 250 and 500 volts; electrodes 9, 13 and 14 with the anode supply voltage of 10 to 18 kilovolts; and sleeve 16 with a focus voltage usually variable over a portion of the range from -100 to +450 volts.

For guns of the prior art, the relative dimensions of

these electrodes are expressed as ratios to the diameter D of cylinder 2.

Cylinder	Diameter	Length	Voltage
1	Outside, $\frac{3}{4}$	0.72	0.
2	Inside, 1	0.87	-30.
4	Inside, 1	0.71 (maximum length)	+275 to 500 v.
9	Inside, 1	1.8 (maximum length)	+10 to 18 kv.

Cylinder	Inside diameter	Length	Voltage
13	1	.77	10 to 18 kilovolts.
14	1	1.02	10 to 18 kilovolts.
16	1.3	1	-100 to +450.

Aperture	Inside diameter
3	.062
6	.072
17	.200
18	.240

Gap, between cylinders, length
2-4
4-9
13-14
0.045

.75

In a typical case the distance between aperture 18 and the center of a 21 inch diameter fluorescent picture-screen is about 18". Voltages listed are potential above the cathode for an assemblage in which D is 0.50 inch.

The electron-optical system in Fig. 2 produces focusing at two points subsequent to the cathode lens; the larger part in the region between apertures 17 and 18; but a still very considerable part in electrode 4 and the region between electrodes 4 and 9. In accordance with my invention, I reduce the latter part to a negligible value by reducing the mean length of screen-grid 4 from .62 D to 0.44 D or less. This results in increasing the focal length of the electron lens formed in and between electrodes 4 and 9 by reducing the curvature of the equipotential surfaces of the electric field within the screen-grid 4 where most of the focussing effect of this lens resides. This change of dimensions also reduces the object distance for this lens so that it becomes small compared to the focal length and makes the focussing effect of the lens negligible.

The above-mentioned increases of focal length of the lens results from reducing the curvature of the equipotential surfaces on the low potential side of the lens. Any other methods of reducing this curvature and/or increasing the focal length are within the broad scope of my invention.

The region of the electron gun between apertures 17 and 18 which is intended to focus the beam must then be slightly changed in a manner known to workers in the field to increase the strength of this lens.

The following advantageous results are attained by this modification of the electron gun:

1. The change of the focussing voltage required when picture brightness changes is greatly reduced; i. e. the change of 250 to 300 volts per 100 microamperes change of beam current in present cathode-ray tubes is dropped by half.

2. The adjustment of focussing voltage required in present tubes with changes in screen-grid voltage is reduced to approximately one-sixth.

3. The adjustment of focussing now required when anode voltage changes, amounting to about 5 percent of the latter, drops to around 3 percent.

4. The defocussing of the electron beam consequent upon the inevitable momentary variations in intensity from point to point in the picture is greatly reduced.

5. The cathode-ray spot size at the picture screen is decreased compared with conventional cathode-ray guns of the same length thus increasing picture resolution in the ratio of from 800 to 1000 lines. This enables receiver designers to attain desired resolution without the necessity for providing supply voltages outside usual values.

6. The percentage of electron beam current which reaches the picture screen will be little affected over a wide range, by the magnitude of the screen-grid and anode voltages.

7. Because the focussing action of the lens between the screen-grid and the first anode has been greatly reduced, ellipticity of cathode-ray spots on the screen is nearly eliminated and asymmetry in the electron lens formed by the screen-grid and first anode produces less aberration and astigmatism in the cathode-ray spot on the picture screen.

8. Non-uniformity and astigmatism in the cathode-ray beam arising from the departures from uniformity in the magnetic field of the ion-trap magnet are greatly reduced when the focussing effect of the screen-grid-to-first-anode lens is reduced by my construction.

9. As a consequence of these advantages the same tube may be marketed for use in makes of receiver having anode voltages from 10 to 18 kv. and screen-grid voltages from 250 to 500 volts, which of our present knowledge includes all the receiver designs which are now sold or have been sold for use with low voltage electrostatically focussed cathode-ray tubes.

Fig. 3 shows an electron gun in accordance with my invention with the length of the screen-grid reduced as just described. The remaining dimensions of the gun structure may be those specified in describing Fig. 2 and guns operating satisfactorily in substantially all picture receivers employing low voltage electrostatically focussed cathode-ray tubes will result. However, it may be found desirable to depart from the dimensions specified in the foregoing tabulation, and I will therefore state in exemplification that the gap between screen-grid 4 and anode 9 may vary between 0.20 D and 0.24 D; the angle of the plane of the inclined rim of screen electrode 4 relative to a plane normal to the axis of screen-grid 4 may lie between ten and thirteen degrees; that the angle between the axes of cylinder-sections 9 and 13 may vary from 0 to 5.5 degrees; that the rolled rim on screen-grid 4 may be omitted; and that a ring or disc of size readily calculated by those skilled in the art may be used in place of cylinder 16.

I claim as my invention:

1. An electron gun comprising a control electrode and a screen-grid electrode, said electrodes comprising coaxial cylinders of inside diameter D having diaphragms normal to their common axis and with apertures lying on said axis, an electron source on said axis on the side of said control electrode aperture remote from said screen-grid electrode, a rim of said screen-grid remote from said control grid lying in a first plane oblique to said axis, the major length of said screen-grid being not over .55 D, a first anode cylinder of diameter D and having a rim adjacent to said screen-grid lying in a second plane parallel to said first plane and separated therefrom by a gap substantially 0.20 D wide, and an electron lens at the other end of said first anode cylinder such that substantially all focussing effect occurs in it.

2. The arrangement specified in claim 1 in which the distance separating said diaphragms is about 0.045 D and the diameter of said apertures therein is about .06 D.

3. An electron gun comprising a control electrode and a screen-grid electrode, said electrodes comprising coaxial cylinders of inside diameter D having diaphragms normal to their common axis and with apertures lying on said axis, an electron source on said axis on the side of said control electrode aperture remote from said screen-grid electrode, a rim of said screen-grid remote from said control electrode lying in a first plane oblique to said axis, the major length of said screen-grid being not over .55 D, a first anode cylinder of diameter D and having a rim adjacent to said screen-grid lying in a second plane parallel to said first plane and separated therefrom by a gap substantially 0.20 D to 0.24 D wide, and an electron lens of substantial focussing power at the other end of said first anode cylinder.

4. An electron gun comprising a control electrode and a screen-grid electrode, said electrodes comprising coaxial cylinders of inside diameter D having diaphragms normal to their common axis and with apertures lying on said axis, an electron source on said axis on the side of said control electrode aperture remote from said screen-grid electrode, a rim of said screen-grid remote from said control electrode lying in a first plane, the length of said screen-grid being not over .44 D, a first anode cylinder of diameter D and having a rim adjacent to said screen-grid lying in a second plane parallel to said first plane and separated therefrom by a gap of about .20 D wide and an electron lens of substantial focusing power at the other end of said first anode cylinder.

5. An electron gun comprising a cathode, a control grid, a screen-grid, a first anode portion, a focusing electrode and a second anode, in the order named, said screen-grid and said first anode comprising coaxial cylinders of inside diameter D having diaphragms normal to their common axis and with apertures lying on said axis, said screen-grid and said first anode portion forming a first electron lens of given focal length on the side of said first lens facing said cathode, said cathode, said control grid and said screen-grid cooperating to form an electron beam object for said first lens within the region of said screen-grid, said screen-grid being of a length of less than .44 D, a rim of said screen-grid remote from said control electrode lying in a first plane and a rim of said first anode portion adjacent said screen-grid lying in a second plane and parallel to said first plane and separated therefrom by a gap of about .20 D, the length of said screen-grid being such that the mid plane between said screen-grid and said first anode portion is at a predetermined distance from said cathode and the principal focus of said first lens is beyond said cathode.
